ATTORNEY

UNITED STATES PATENT OFFICE.

JACOB Y. KLINE, OF FLORIN, PENNSYLVANIA.

LIFTING-JACK.

1,024,860.

Specification of Letters Patent. Patented Apr. 30, 1912.

Application filed April 26, 1911. Serial No. 623,387.

To all whom it may concern:

Be it known that I, JACOB Y. KLINE, a citizen of the United States, residing at Florin, in the county of Lancaster and State of Pennsylvania, have invented certain new and useful Improvements in Lifting-Jacks, of which the following is a specification, reference being had therein to the accompanying drawing.

10 This invention relates to a lifting jack of that class intended for use in lifting vehicles, etc., and also as a press for pressing the covers on tobacco cases and the like.

The object of the invention is to produce 15 a jack that shall be cheap, durable, contain few parts and be simple of operation.

Another object of the invention is to provide a jack that has no positive stop for each stroke of the lever, but which is capable of 20 varying adjustment or throw.

Still another object of the invention is to so construct the jack that the load may be gradually lowered and not allowed to drop as is the case in many frictional jacks.

25 With these and other objects in view, my invention consists in certain construction and combination of parts as will hereinafter be fully described and claimed in the accompanying drawings which form a part of this application, and in which like figures of reference refer to corresponding parts in all of the views; but it is fully understood that while I have here described my invention as shown, that I do not confine myself 30 to the exact design, as slight changes may be made in the construction and arrangement of the several parts without departing from the spirit of the invention.

In the drawings:—Figure 1, is a side elevation of the jack showing the hand lever in position for raising, and the position of the same at the end of the stroke is indicated in dotted lines. Fig. 2, is a rear end elevation of the same. Fig. 3, is a top plan 45 view partly in section, taken on the line X—X of Fig. 1. Fig. 4, is an enlarged detail sectional view of the bracket and friction links.

Referring to the drawings, the device 50 comprises a standard 1, to which is secured a base 2, and a bracket member 3. Said bracket 3, is formed with a guide arm 4, having an orifice in axial relation with the pipe standard 1, to receive the lifting bar 5. 55 The bracket 3, is further provided with a lug 6, upon which is pivoted by the pin 7,

the bifurcated end 8, of a hand lever 9. The lifting bar 5, is movably mounted in the standard 1, and guide arm 4, and has secured upon the upper end thereof a bearing 60 cap 10.

Upon the lifting bar 5, between the guide arm 4, and the upper end of the standard 1, are mounted the frictional lifting link 11, and the check link 12. The lifting link 11, 65 is formed with a projection 13, for engagement by the ends 8, of the hand lever; and also has the finger ears 14, which embrace the sides of the bracket 3, and serve as a guide for said link. The check link 12, is 70 formed with a bifurcated end 15, for engaging the sides of the bracket 3, near the arm 4, and which rest upon the shoulders 16, formed on said bracket 3, to prevent the link from slipping downward, but allowing 75 it to rock; the forward end of said check link 12, being provided with a pair of finger ears 17, similar to those on the lifting link 11. On the up stroke of the hand lever 9, the check link 12, will frictionally grip the lifting bar 5, by reason of 80 its gravity and hold the lifting bar 5, from lowering until released by lifting the ears 17, with the operator's fingers. On the down stroke of the hand lever 9, the end 8, 85 engages the projection 13, of the link 11, which has descended by gravity to its lowest position allowed by the end 8, of the hand lever 9, and raises the lifting bar 5, by the frictional grip of said lifting link 90 11, on said bar; the operation being repeated for each stroke of the hand lever. For letting down the load, the lifting link 11, is raised by the operator's fingers to the positions indicated by the dotted 95 lines in Fig. 1, and is there held by the hand lever 9, while the check link 12, is released, when the lever is raised, lowering the bar, and the operation repeated.

Having thus described my invention 100 what I claim as new and desire to secure by Letters Patent is:—

In a lifting jack of the class described, the combination with a hollow standard and base formed with a bracket and guide 105 arm and having a lifting bar movably mounted in said standard and guide arm, of a check link mounted on said lifting bar adjacent to said guide arm and formed with a bifurcated end engaged by said 110 bracket, shoulders formed on said bracket for engaging the bifurcated end of said

check link and limiting the downward movement of the same, a lifting link mounted on said lifting bar below said check link, said lifting link formed with a bifurcated end engaging said bracket to prevent said link from turning, a projection formed on said link, a hand lever pivoted to said bracket, and a bifurcated end formed on

said hand lever for engaging the projection on said link for lifting the same.

In testimony whereof I affix my signature in presence of two witnesses.

JACOB Y. KLINE.

Witnesses:

Wm. J. COULTER,

JOHN J. THOMPSON.
